UNITED STATES PATENT OFFICE.

JAMES R. SMITH AND PARSKILL E. WILLIAMS, OF RYAN, OKLAHOMA.

BED.

1,088,468.

Specification of Letters Patent.

Patented Feb. 24, 1914.

Application filed October 7, 1913. Serial No. 793,953.

To all whom it may concern:

Be it known that we, JAMES R. SMITH and PARSKILL E. WILLIAMS, citizens of the United States, residing at Ryan, in the county of Jefferson and State of Oklahoma, have invented new and useful Improvements in Beds, of which the following is a specification.

This invention relates generally to an improvement in beds and particularly to an auxiliary bed structure connected with the main bed and adapted to be moved into a position to one side of the main bed for use or to a position wholly beneath the main bed when not desired for use.

The main object of the present invention is the provision of an auxiliary bed structure including a means removably secured to the main bed and slidably supporting the auxiliary bed, whereby the auxiliary bed may be moved laterally with relation to the main bed, the entire structure being readily separable from or connectable to the main bed in a simple, expeditious manner.

The invention in its preferred form of details will be described in the following specification, reference being had to the accompanying drawing, in which:

Figure 1 is a perspective view of the improved bed, the auxiliary bed being extended. Fig. 2 is a plan view of the same with the auxiliary bed in inoperative position. Fig. 3 is a longitudinal section of the same. Fig. 4 is a perspective view of one of the guide bars for connection with the main bed. Fig. 5 is a perspective view of one end of the auxiliary bed removed. Fig. 6 is a sectional detail view of one corner of the auxiliary bed, showing the leg structure therefor.

Referring particularly to the accompanying drawings, the main bed may be of any usual or preferred construction, that shown being the usual type of metal bed including the head piece 1, foot piece 2 and angle side bars 3 on which the usual spring frame is designed to be set in the use of the main bed.

While showing and describing the invention in connection with a metal bed it is to be understood that it is equally adaptable to wooden beds, the sole difference in structure being in the relative adjustment of the size of the parts to coöperate with the side rails of the wooden bed which as is well

known differ from the side rails or bars of the metal bed.

The auxiliary bed includes guide rails 4 designed to be removably secured to the side rails of the bed. These guide rails are of identical structure, preferably constructed of a single strip of metal formed to provide a bearing flange 5 which at its lower end is formed in a return bend and projected upwardly to form a second guide flange 6, said flange 6 being of less height than the flange 5 and disposed in approximate parallelism therewith. The holding means for the guide rails include clips 7 having parallel relatively offset bearing sections 8 and 9, the latter being designed to be secured to the flange 4 of the guide rail on the upper surface thereof while the former is designed to overlie the horizontal flange of the side rail of the bed, being sufficiently offset from the relatively upper surface of the guide rail as to receive the horizontal flange of the bed side rail between the section 8 and the upper surface of the flange 4 of the guide rail. To permit the guide rails to be removably secured to the side rails of the bed one or both of the clips 7 may be slidably connected to said guide rail as for example by forming a slot in the section 9 of the clip to receive a set screw passing through the flange 4 of the guide rail, by which means the clips may be withdrawn to their limit of inward movement, the guide rails positioned against the horizontal flanges of the bed rails from beneath and the clips moved outwardly to engage above said side rails and clamped in position. The guide rails are thus fixedly secured to the bed structure, being of course located a proper distance apart to receive the auxiliary bed between them. The auxiliary bed comprises a frame 10 including end rails 11 and the side rails 12, the latter being of angle shape to prevent lateral slipping of the mattress placed thereon. Within the frame 10 is secured any desired type of bed spring 13, and I do not limit myself in any degree concerning this particular feature of the invention. The end rails 11 which are of angular form are each provided with a guide member to coöperate with the guide rails secured to the main bed which guide member comprises a metallic strip having its upper end bent downwardly in return form as at 14 extending in parallelism with the main section 15 of the guide strip, the lower end of the guide

strip being projected upwardly to form a guide flange 16. The upper edge of the guide strip 16 extends above the lower edge of the guide strip 14, and said strips 14 and 5 16 are in parallelism with each other though spaced apart.

In the sliding coöperation of the parts, the guide flange 14 of the guide strip is positioned between the flanges 5 and 6 and 10 of the guide rail, the main strip 15 of the guide strip bearing against the outer surface of the flange 6, while the flange 16 of the guide strip bears against the outer surface of the flange 5 of the guide rail. By 15 this arrangement the guide strip is slidably mounted in the guide rail while at the same time it is prevented from vertical movement in either direction while so connected. This is important in order to prevent a tilting 20 of the auxiliary bed when fully extended, and in connection with such arrangement it will be noted that the extension of the guide strips beyond one side rail of the auxiliary bed frame forms an extended bearing with 25 said guide strips on the guide rails when the auxiliary bed is extended to proper position, as clearly shown in Fig. 1. The inner ends of the auxiliary bed are supported by the guide rails when the auxiliary bed is ex- 30 tended, and to support the outer end of said auxiliary bed I provide legs. For compensating for any floor covering or other obstruction the legs of the auxiliary bed should be adjustable as to height, and this is pro- 35 vided for in the present improvement. The legs are of identical structure and bolted to the frame of the auxiliary bed, so that said sections may be readily removed when de- 40 sired to pack the auxiliary bed for storage or shipment. Brace bars 19 are removably connected to the main lengths 17 and to the end rails of the auxiliary bed by removable bolts to permit the disconnection of these 45 parts when desired. Slidably mounted in the main lengths 17 of the legs are posts 20 held in adjusted position within said main lengths 17 by set screws 21, the lower or free ends of the posts 20 being provided with casters or other similar devices 22. 50 From Fig. 1 it will be noted that the auxiliary bed may be readily extended to a po-

sition wholly to one side of the main bed and thus affords an increased width of said main bed for any desired purpose, and that when not desired for use the auxiliary bed may 55 be readily moved to a position beneath the main bed and wholly out of the way. The auxiliary bed with its coöperating parts forms a structure wholly independent of the main bed, and may be readily removed 60 therefrom or connected thereto when desired, such operation requiring only the manipulation of the clips 7 to release the guide rails from the main bed side rails, whereupon the entire structure may be 65 wholly separated from the main bed and stored until again required. When in inoperative position the auxiliary bed is wholly out of the way and in fact cannot be seen when the main bed is dressed in the usual 70 manner, so that by my invention a simple means is provided which for emergency uses may be caused to increase the width of any bed structure for use and enable, for example, a single bed to be readily made into 75 a double bed for sleeping purposes and collapsed to a single bed when not desired for sleeping purposes. This advantage alone is important in restricted quarters.

What is claimed is:

The combination with a main bed, of 80 guide rails removably secured thereto and comprising metallic strips bent to form spaced parallel flanges and clips slidably connected to said guide rails and movable 85 to embrace the side rails of the bed between the clips and guide rails, an auxiliary bed comprising a spring carrying frame having end rails of greater length than the width of the frame, each of said end rails being 90 formed to provide guide strips including spaced parallel flanges to embrace the outer sides of the parallel flanges of the guide rails and an intermediate flange to slide between the parallel flanges of the guide rails. 95

In testimony whereof we affix our signatures in presence of two witnesses.

JAMES R. SMITH.
PARSKILL E. WILLIAMS.
